Primary Examiner — Selina Sikder

(57) **CLAIM**

The ornamental design for the multi-electrode holder, as shown and described.

DESCRIPTION

FIG. 1 is a perspective view of a multi-electrode holder incorporating my design;
FIG. 2 is a left-side view of the multi-electrode holder;
FIG. 3 is a right-side view of the multi-electrode holder;
FIG. 4 is a front view of the multi-electrode holder;
FIG. 5 is a rear view of the multi-electrode holder;
FIG. 6 is a top view of the multi-electrode holder; and,
FIG. 7 is a bottom view of the multi-electrode holder.
The broken lines are for illustrative purposes. None of the broken lines form part of the claimed design.
